UNITED STATES PATENT OFFICE.

THOMAS HARDY, OF MANCHESTER, ENGLAND, ASSIGNOR TO T. HARDY AND COMPANY LIMITED, OF MANCHESTER, ENGLAND.

FASTENING MEANS FOR GARMENTS.

Application filed March 10, 1924. Serial No. 698,070.

To all whom it may concern:

Be it known that I, THOMAS HARDY, a subject of King George V of Great Britain, residing at 68 Alexandra Road, Moss Side, 5 Manchester, in the county of Lancaster, England, have invented certain new and useful Improvements in Fastening Means for Garments, of which the following is a specification.

- 10 This invention relates to fastenings for garments and more particularly for aprons of the kind in which elastic is placed in a hem at the top to render said top expandible and has for its object to provide firm and 15 efficient fastening means which are readily applied when making up the apron and which can be readily removed when it is desired to wash the apron and reapplied afterwards.
- 20 According to the invention the improved fastener comprises a hook-like fitting formed of wire bent to a U-shape the free ends of 25 which are bent over at right angles so as to overlap to form a cross bar on to which the elastic at one side of the apron can be threaded through an opening left between the overlapping ends when removing or replacing the device. The other end of the fitting is bent over along a line parallel to 30 said cross-bar to form a hook adapted to engage a complementary fitting attached to a loop at the end of the elastic at the other side of the apron and which may consist of a plain ring of metal or bone or the like or 35 of a metal wire ring formed with overlapping ends in like manner to the hook.

The invention will be more particularly described by the aid of the accompanying drawings wherein:—

- 40 Figure 1 is a perspective view of the hook like fitting made according to one form of the invention,

- Figure 2 is a perspective view of the "ring" forming the complementary part of the fastening,

Figure 3 is a perspective view showing the parts illustrated in Figures 1 and 2 attached to an elastic waist band of a garment,

- 45 Figures 4, 5, 6 and 7 are views of the hook-like fitting in various stages of manufacture.

Figure 8 is a side view of Figure 7,

Figures 9, 10 and 11 are views of the "ring" in various stages of manufacture,

Figure 12 is a side view of Figure 11, 55

Figures 13 and 14 are face views of a further modified form of hook and ring, while Figures 15 and 16 are plan views of Figures 13 and 14 respectively.

In carrying the invention into effect according to one convenient manner as illustrated in Figures 1 to 12, the hook-like fitting *a* is formed of wire, preferably non-corrodible, which is first bent to a U-shape *b* as shown in Figure 4. Then the end *c* of one limb is bent over at right angles, as shown in Figure 5, so that it nearly meets the other limb. The end *d* of the other limb is then bent over as seen in Figure 6 to overlap the end *c*, the two ends *c*, *d* constituting the cross-bar. The other end of the fitting is then bent over as shown in Figures 7 and 8 to form the hook proper *a*.

The ring is formed somewhat in like manner to the hook, Figures 9, 10 and 11 showing the successive stages of manufacture while Figure 12 is an edge view of the finished ring.

Referring to Figures 1 and 2 which show the finished hook and ring respectively it will be seen that the loops of elastic *f*, *g* at the respective edges *h*, *i* of the apron can be readily threaded thereon as seen in Figure 3 and as easily removed for laundry or other purposes.

Figures 13 to 16 show a construction of hook and ring formed from wire somewhat after the manner of the hook eye shown in Figures 1 and 2 but with the limbs of the hook portion bent inward to lie side by side and the eye modified to suit the same.

By these means the edges of such aprons or other garments are readily fastened together and when fastened cannot burst asunder, moreover the fastening means are readily applied and removed for laundry and other purposes.

Having now particularly described and ascertained the nature of my said invention and in what manner the same is to be performed I declare that what I claim is:—

As a new article of manufacture detachable fastening means for aprons and the like formed from two pieces of wire, the mid

portion of one of which is shaped to form an eye, while the mid portion of the other is shaped to form a complemental hook, and having the free ends of both pieces of wire overlapped, parallel and in spaced relation relatively to each other, providing a free passage leading to the interior of each member whereby a garment loop may be readily

slipped through the passage, thereby quickly attaching or detaching the fastening to or ¹⁰ from the garment.

In testimony whereof, I have signed my name to this specification at Manchester, this 21st day of February, 1924.

THOMAS HARDY.
